CLAIM

The ornamental design for a shoe, as shown and described.

DESCRIPTION

FIG. 1 is a front perspective view of a shoe showing my new design;

FIG. 2 is a side view thereof; and,

FIG. 3 is a rear perspective view thereof.

The broken lines immediately adjacent to the panel containing the grey filled regions define the bounds of the claimed design and form no part thereof. The grey filled regions represent a contrast in appearance relative to the remainder of the panel and do not represent any particular color, material, texture or finish. The broken lines depicting the remainder of the shoe form no part of the claimed design.
